COUPLING

Richard C. Coupland, United States Army,
Norfolk, Va.

Application July 10, 1934, Serial No. 734,561

2 Claims. (Cl. 89—27)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a coupling.

The purpose of the invention is to provide a coupling between a member and a support which may be quickly and easily operated in coupling and uncoupling and which will afford a firm and 10 secure attachment.

A further object of the invention is to provide a coupling in which it is only necessary to act on a single member to couple or uncouple the member and the support.

15 To these and other ends the invention consists in the construction, arrangement and combination of elements described hereinafter and pointed out in the claims forming a part of this specification.

20 A preferred embodiment of the invention is illustrated in the accompanying drawing in connection with a trigger motor housing that is to be associated with a machine gun.

Fig. 1 is a view in side elevation of the breech 25 casing with the housing attached.

Fig. 2 is a sectional view on the line 2—2 of Fig. 1.

Fig. 3 is an inside plan view of the housing.

Fig. 4 is a sectional view on the line 4—4 of Fig. 2.

Figs. 5 and 6 show detail views in plan and elevation of the bell crank lever.

Referring to the drawing by characters of reference there is shown the breech casing of a machine gun including a pair of spaced side walls 5—5. The side walls are each provided with a pair of slots or apertures, the rear aperture 6 having its rear face 7 inclined forwardly from inside to outside of the breech casing and the front aperture 8 having its front face 9 inclined rearwardly from inside to outside of the breech casing. The faces 7 and 9 are therefore outwardly convergent or inwardly divergent.

A housing 10 adapted to be mounted on, and 5 bear against either one of the side walls 5—5 of the breech casing is formed with a pair of lugs 11 and 12 respectively entering the apertures 6 and 8. The lug 11 has an inclined face 13

complementary to and adapted to bear against the inclined face 7 of the rear aperture.

The lug 12 carries a bell crank lever 14 mounted on a pivot pin 15. One arm 16 of the lever corresponds to the lug 11 and has an inclined face 17 complementary to and adapted to bear against the inclined face 9 of the front aperture 8. The other arm 18 of the lever is bifurcated to straddle a nipple 19 on the front end of the housing 10. A nut 20 threaded on the nipple bears against 10 the bifurcated arm 18, holds it immovable against the shoulder 21 of the housing and thereby forces the inclined faces 13 and 17 of the housing into engagement with the inclined faces 7 and 9 of the side wall 5.

A half turn of the nut 20 frees the bell crank lever sufficiently to enable the housing to be detached by an outward movement of its front end. The attachment of the housing to the side wall 5 of the breech casing is accomplished by reversing this operation. When the nut is tight the housing is securely held in place on the side wall of the breech casing.

15 I claim:

1. In a coupling, a support having oppositely inclined surfaces converging outwardly, a member on the outside of the support and having a reduced end, a fixed inclined surface on said member for engaging one of the inclined surfaces of the support, a bell-crank lever fulcrumed on 30 said member, one arm of the lever having an inclined surface for engaging the other inclined surface of the support, the other arm of the lever straddling the reduced end of the member, and a nut on the reduced end of the member holding 35 said other arm against the support.

2. In a coupling, a support having oppositely inclined surfaces converging outwardly, a member on the outside of the support and having a reduced end, a fixed inclined surface on said member for engaging one of the inclined surfaces of the support, a lever fulcrumed on said member, one arm of the lever having an inclined surface for engaging the other inclined surface of the support, and a nut on the reduced end of the 45 member holding said other arm against the support.

RICHARD C. COUPLAND.
